TAMPON AND APPLICATOR

John C. Bletzinger, Neenah, and Howard A. Whitehead, Appleton, Wis., assignors to Kimberly-Clark Corporation, Neenah, Wis., a corporation of Delaware

Filed Aug. 27, 1962, Ser. No. 219,384

3 Claims. (Cl. 128—263)

This invention relates to improvements in catamenial tampons and more specifically to tampons employing a tubular applicator and requiring directional insertion for optimum results.

An important object of the invention is to provide an improved tubular applicator adapted accurately to position a tampon in predetermined orientation within the vaginal canal.

Another object is to provide an improved tubular applicator permitting the directional insertion of a compressed tampon of generally cylindrical configuration but adapted when wet anatomically to conform to the transverse shape of the vaginal canal.

Other objects and advantages will become apparent to persons skilled in the art upon examination of the drawings and description, as will various modifications and adaptations of the concepts herein taught.

In the drawings, in which like parts are identified by the same reference numerals,

FIG. 1 illustrates in perspective a tampon and a tube type applicator, each incorporating the inventive concept.

FIG. 1a shows a tampon plectet prior to being compressed into cylindrical configuration as illustrated in FIG. 1.

FIGS. 2, 3, 4 and 5 illustrate in perspective tampons and applicators incorporating various modifications of the invention.

Tubular tampon applicators are well known and perform satisfactorily for insertion of non-directional type tampons within the vaginal canal. The present invention is directed specifically to improved tampon applicators of the tubular type but adapted for the directional insertion of a generally cylindrical anatomically designed tampon which upon fluid expansion conforms to the configuration of the vaginal canal.

The present invention has particular utility when employed in association with an anatomically designed tampon resulting from the compression into cylindrical form of a tampon plectet of the general configuration shown at 10 in FIG. 1a. A co-pending patent application filed August 27, 1963, Serial No. 219,395, by Howard A. Whitehead, a co-inventor of the present concept, teaches a method of fabricating tampons from plectets of sponge material contoured as in FIG. 1a. Following compression of the plectet 10, which may comprise a relatively thick keystone shaped blank 12 of sponge or foam material, blank 12 is drawn into a "dog-bone" configuration in transverse section by one or more threads 20 sewn along the longitudinal axis thereof to maintain the desired configuration. As taught in said co-pending application, the plectet 10 is then compressed into cylindrical form and thereafter transferred into a cartridge-like tubular body portion of an applicator. The present invention is directed to improvements in tubular applicators of the type adapted to house highly compressed cylindrical batts formed from and fluid expandable into anatomically contoured plectets.

2

FIG. 1 illustrates in perspective and partially cut away the combination of an improved tubular telescopic type applicator 16 consisting of a cartridge-like element 18 adapted to receive a compressed tampon batt, and a telescopically associated tubular plunger element 20 for ejection of a housed tampon batt from cartridge 18 after insertion in the vaginal canal. FIG. 1 shows a highly compressed fluid absorbent batt 22 spaced from a cartridge-like applicator portion 18, it being understood that batt 22 which has been formed by compressing into cylindrical form the plectet 10 of FIG. 1a, is adapted to be completely received and housed in portion 18.

FIG. 1 shows cylindrical batt 22 provided with a pair of diametrically disposed and axially extending guide channels 24, 26. Cartridge-like applicator portion 18 is internally provided with a pair of diametrically disposed and axially extending guide ribs 28, 30 positioned for registry with the tampon guide channels 24, 26 with batt 22 snugly disposed in applicator portion 18. The combination of ribs and guide channels effectively prevents relative rotation of batt 22 within tubular applicator portion 18 while permitting relative axial movement therebetween.

The FIG. 1 structure also illustrates the tubular plunger portion 20 of applicator 16 provided with a pair of diametrically disposed and axially extending guide channels 32, 34 positioned for slidable association with the internal cartridge ribs 28, 30, respectively, to prevent relative rotation between tampon plunger 20 and portion 18 in which batt 22 is housed. It is not essential, however, that the plunger be constrained from rotating within the batt containing cartridge portion 18. During use the right hand end of tampon 16 is first inserted into the body. The opposite end of the cartridge-like tube 18 is provided at 36 with an aperture or with some other touch sensitive or visual indicating means whereby cartridge portion 18 may be maintained in a predetermined optimum position either during or after insertion. With tampon applicator 16 properly positioned within the vaginal canal, ejection of batt 22 by the depression of ejector tube 20 is effected in the absence of relative rotation between batt 22 and cartridge 18, thus insuring the proper positioning within the body of the compressed batt 22. When wet, the batt reexpands to the configuration of FIG. 1a and is properly positioned within the user's body to insure optimum effectiveness and comfort.

The concept, as incorporated in the structure of FIGS. 1 and 1a, is subject to numerous alterations. FIG. 2 illustrates in enlarged perspective the tampon batt and cartridge shown in FIG. 1 wherein the batt is externally fluted and the cartridge is internally ribbed.

FIG. 3 illustrates a cartridge 18a internally fluted by depression of the cartridge side walls after formation.

FIG. 4 illustrates a tampon batt 22c and an associated cartridge 18c, batt 22c being externally fluted in a somewhat different manner than shown in FIGS. 1 and 2, and cartridge 18c being internally ribbed in a manner to complement the fluting of batt 22c.

FIG. 5 illustrates an alternate embodiment of the invention wherein a compressed tampon batt 22d is provided with an axially ribbed area confined to a portion of the circumference of the batt and cartridge 18d is provided internally with similar ribs for the complementary reception of the batt 22d.

We claim:

1. In a device for the directional placement of a tube-
5 enclosed preshaped tampon in the vaginal canal including
a cylindrical tubular applicator, a plunger element and a
compressed batt of preshaped fluid absorbent material
disposed in predetermined orientation within said applicator,
the improvement comprising means associated
with said applicator to prevent relative rotation of said
batt within said applicator while permitting axial ejection
therefrom whereby said tampon may be directionally 10
positioned in the vaginal canal, said means consisting
of an axially extending rib on the interior wall of said
applicator tube and a complemental axially extending
groove on the exterior of said batt for registered com-
plemental engagement with said rib, said tube also in-
cluding exterior indicator means for positioning thereof
during batt ejection.

2. The device of claim 1 in which the rotation pre-
venting means in said applicator consists of a plurality

15 of axially extending ribs on said interior wall and a plu-
rality of matching axially extending grooves on the ex-
terior of said batt.

3. The device of claim 1 in which the plunger ele-
ment is a close fitting tube having on its exterior wall
a complemental groove for registration with the interior
rib in said applicator, said plunger element also having
exterior indicator means for positioning during use.
